[57] **ABSTRACT**

To reduce the packing space of game playing boards, which are formed with depressions to place game chips or the like therein, a plate member is formed with a preferably central opening into which a plastic body can be inserted. The plastic body has the depressions therein into which the chips can be placed. The plate member itself is formed with a fold line. The plastic body has a laterally projecting flange underlying the fold line and projections which fit into openings with an interference fit so that the plastic body can be pushed into the opening of the plate when the game is to be played, and can be removed therefrom, and the plate-like board folded.

1
FOLDABLE GAME PLAYING BOARD

The present invention relates to a game board, and more particularly to a game board for games which use chips or other markers or elements which are placed by the players into depressions, or formed locations, on the board.

Many games use game boards which are printed with indicia depending upon the game to be played. In many types of these games, chips, marker pins, or other symbolic shapes or figures are placed on specific locations on the board. For ease of playing, or as provided by the rules, these game boards are often formed with depressions into which the chips or markers are to be placed. If these game boards are to be formed with depressions, however, then manufacture of the boards from cardboard itself presents difficulty. It is simple to make such boards of wood and form or groove the depressions therein, or to make them of plastic material as a molding or punched game board directly formed with the depressions. Such formed or shaped game boards have the disadvantage that they are comparatively expensive in manufacture and additionally that their three-dimensional profile prevents ready folding of the board so that packaging, storing, and display require substantial additional material and space. The final dimensions of the game board eventually determine the size of the carton for packaging and if the board is to be of substantial size to accommodate a number of players, the size of the package quickly becomes unwieldy.

It is an object of the present invention to provide a game board which has a three-dimensional profile, in that it is formed with depressions to accept chips, or other figures or elements to be used in the game, and which nevertheless can be folded for storage in a comparatively small space, and which is inexpensive to make.

**SUBJECT MATTER OF THE PRESENT
INVENTION**

Briefly, a plate-like board member is provided which is formed with an opening, for example centrally located. A plastic formed, three-dimensional body having the depressions therein is removably inserted in the opening. The plastic body is itself shaped such that the region fitting against the opening is formed as an upstanding projecting rim, or the like, beyond which a flange extends, adapted to underlie (or overlie) the plate-like board. The projections matching against the rim fit therein with a slight interference fit, to be frictionally retained. When the game is to be played, the plastic body is inserted in the opening; for storage, the plastic body is removed and the flat plate-like board can then be folded to an outline which is much less than the size of the unfolded, flat board. In a preferred form, the opening in the board is circular and centrally located; additional locating holes may be provided in the board, which fit over locating projections formed on the plastic body. These projections may be slightly conical.

The invention will be described by way of example with reference to the accompanying drawings, wherein:

FIG. 1 is a plan view of a board in accordance with the present invention; and

FIG. 2 is a cross-sectional view along line II-II of FIG. 1, to an enlarged scale.

2

The board 1 is preferably of cardboard, pressboard or similar material. Its upper side may have a printed game configuration, schematically indicated at 2, applied thereto. The particular type of printing will depend on the game to be played. The board is formed with a circular central opening 3. Opening 3 need not be circular, but may have any other shape, for example square, triangular, or as desired. The opening need not be placed centrally of the game board but may be placed eccentrically; if required by the rules of the game, more than one opening may be provided in the board.

A plastic, three-dimensionally shaped body 4 is located in the opening 3. It is removably inserted with a slight interference fit formed by a surface 6 and extending beyond the thickness of plate 1, fitting into opening 3. The body 4 is formed with depressions 5 to accept chips, figures, or the like to be used in the game. A laterally extending flange 7 having an end edge 7' projects from the side surface 6 to form a bearing stop for the lower portion of board 1. Flange 7 may be formed with upwardly extending projections 8 fitting into corresponding holes 9 in board 1. Projections 8 are preferably slightly conical. If the body 4 is not round, but so shaped that it can be located only in a predetermined orientation with respect to board 1, then projections 8 may be omitted.

Board 1 itself can be folded across a fold 10 arranged along a folding line passing through the opening. More than one such folding line can be provided, for example another one at right angles thereto so that the board 1 can be folded in two directions to form a small square essentially fitting within, or closely over, the outline of plastic body 4.

To play the game, board 1 is unfolded flat and body 4 inserted therein with the interference fit of surface 6 fitting against the inside wall of opening 3, and the lower surface of board 1 fitting against flange 7, projections 8 fitting into their matching holes 9.

Various changes and modifications may be made and the particular arrangement of the board itself, the printing thereon, and the arrangement of the depressions as shown in the drawings will follow from the nature of the game to be played and its rules and may be arranged accordingly.

I claim:

1. Game board comprising
50 a foldable plate member (1) formed with an opening (3) therein and foldable about a fold line (10) extending through the opening;
a board-like body (4) of plastic material, the plastic body (4) being formed with a projecting portion (6) fitting into the opening (3) with an interference fit, and further formed with laterally projecting flange portions (7) extending laterally beyond said projecting portion (6) and locatable against a face of the foldable plate member (1) to support the foldable plate member in flat, unfolded condition and to so hold the plate member by the interference fit.

2. Game board according to claim 1, including upwardly extending projections (8) formed on said flange portions (7);

and openings (9) formed in said plate member matching the locations of said projections.

3. Game board according to claim 2, wherein said projections (8) are conical.

4. Game board according to claim 1, wherein said opening (3) is located centrally with respect to said plate member.

5. Game board according to claim 1, wherein the plastic board-like body (4) has depressions (5) formed in the projecting portion (6) thereof.
